UNITED STATES PATENT OFFICE.

WILLIAM SPERLING, OF NEW YORK, N. Y., ASSIGNOR TO ROSE SILVER COMPANY, OF NEW YORK, N. Y., A FIRM CONSISTING OF E. ROSENBERG AND WILLIAM SPERLING.

SUGAR RECEPTACLE.

Application filed February 24, 1923. Serial No. 620,865.

To all whom it may concern:

Be it known that I, WILLIAM SPERLING, citizen of the United States of America, residing at New York city, in the county of Bronx and State of New York, have invented new and useful Improvements in Sugar Receptacles, of which the following is a specification.

My invention relates generally to improvements in sugar receptacles for table use, and has specific reference to the construction of an article of this character which is provided with an integral spoon rack adapted to support a service of tea spoons about the periphery of the bowl.

Generally a sugar service of this description is provided with a pair of separate cast spoon racks which are soldered to a section of the receptacle and from which the spoons themselves are suspended. The step in manufacturing this article which consists in soldering the castings in position is considered a rather delicate operation and the results obtained are not always satisfactory, principally where the solder does not "run" well and more especially where the heat from the soldering torch causes a distortion in the casting. Furthermore, the use of such castings makes the cost of manufacture relatively high, the castings themselves being rather expensive and the labor and time required to solder them to the shell of the receptacle being considerable. Neatness in this type of metal work is very essential and cumbersome soldered joints and projecting parts tend to mar its general appearance.

With the foregoing in mind, the principal object of the invention is to eliminate the rack castings altogether and to substitute therefor an integral spun flange which projects marginally about the periphery of the receptacle and which is provided with radially disposed slots to receive and support the spoons in the usual manner. I accomplish this object by providing the metal blank, from which the upper section of the receptacle is spun, with a band of marginally projecting stock in which radial slots are stamped at the time the blank is cut from the metal. The cut blank is thereafter spun into the desired shape and the marginal band then becomes a flange projecting laterally therefrom and may be utilized for the spoon rack, as hereinafter described.

A further object of the invention is to

provide an article of this character, which will be strong and durable in construction, and which will afford the desired neatness in appearance and at a greatly reduced manufacturing cost over the type employing the separate spoon rack castings.

The invention is illustrated in the accompanying drawing, in which, Figure 1 is a side elevational view of my improved sugar receptacle, showing the integrally spun spoon rack, and also with parts illustrated in section to disclose the general construction; Figure 2 is an enlarged detail sectional view of the upper sections of the receptacle; and Figure 3 is a plan view of the receptacle showing the arrangement of the spoon rack.

Referring to the drawings, 10 denotes the foot section comprising a spun annular shell having a reduced upper portion to receive and support the bowl proper of the receptacle. The bowl consists of three sections, the lower or body portion of which is hemispherical or cup shaped as indicated by 11, and is soldered or otherwise attached to the reduced end of the pedestal 10. The open upper end of the part 11 is provided with an outwardly projecting annular flange 12 against which is soldered the lower edge of the neck 13, the latter being provided with oppositely disposed handle members 14. The third section or collar indicated at 15, constitutes the bezel support for the cover 16, and comprises an annular member having a curved midportion 17 terminating at the upper elevation in an upright flange 18 for centering the cover 16, and the lower edge thereof being disposed outwardly by spinning the marginal portion of the metal at right angles to the general axis of bezel. This marginal portion becomes the spoon rack 19 and is provided with radially disposed slots or openings 20 in which the spoons may be suspended. The bezel 15 is attached to the upper edge of the collar 13 by placing the under surface of the flange 18 or rack 19 against the edge of the collar 13 and allowing solder to "run" between the two members in the usual manner.

In the embodiment of the invention shown in the drawing the flange rack 19 is divided into quadrants, i. e. two opposite portions of the flange are of greater width than the alternate portions thereof and are the portions in which the spoon slots 20 are disposed, while the narrower portions are ar-

ranged so as to coincide with the positions of the handles 14 as clearly illustrated in Figure 3. The rigidity of the rack 19 is further increased by the provision of curved 5 ribs 21 stamped up about the walls of the slots 20.

Subsequent to the receptacle being assembled and the parts and sections being soldered or otherwise attached together the 10 article is subjected to a plating process which gives it luster and finish and completes the article.

Having described my invention what I claim is:—

15 A receptacle comprising a hollow base member, a bowl shaped section supported on and welded to said base member and having its free edge turned outwardly to form a

flange, an upright annular band superposed on and soldered to said flange, a handle member attached to said band and adapted to be assembled with said band before the latter is attached to the bowl, and a bezel section comprising a curved midportion terminating at its lower edge in an outwardly projecting flange having a series of cut out portions to receive the narrow portion of spoons, the inner edge of the latter flange being adapted to coincide with the inner edge of the upright band to which the bezel is soldered, the opposite upper free end of the bezel comprising an inverted upright U-shaped collar projecting from the curved portion.

In testimony whereof I affix my signature.
WILLIAM SPERLING.
